UNITED STATES PATENT OFFICE.

HAROLD J. GOSS, OF NASHUA, NEW HAMPSHIRE, ASSIGNOR TO ELIE W. LABOM-BARDE, OF NASHUA, NEW HAMPSHIRE.

BLANK-OPERATED MECHANISM.

Application filed January 31, 1924. Serial No. 689,636.

To all whom it may concern:

Be it known that I, HAROLD J. Goss, a citizen of the United States, and resident of Nashua, in the county of Hillsborough and 5 State of New Hampshire, have invented a new and useful Blank-Operated Mechanism, of which the following is a specification.

The principal object of my invention is to improve the operation of machines operating on blanks and especially on very thin 10 blanks such as those used in making envelopes.

The principal feature of my invention consists in providing mechanism operated 15 by the passage of a blank which mechanism operates to affect the blank after such passage.

A particular feature is a trip mechanism operated by a passing blank to release for 20 action mechanism to bring a glue roll into subsequent cooperative engagement with said blank.

Another feature is particular cam mechanism for controlling said action.

25 Other features will be pointed out below.

In the drawing

Figure 1 is a plan of a portion of a blank feeding and gluing machine embodying my 30 invention;

Figure 2 is an elevation of the same; and

Figure 3 is an enlarged elevation of the cam mechanism described below; and

Figure 4 is a plan of the cam.

35 I illustrate my invention as embodied in an envelope making machine in which A A' represent side bars of any suitable frame and connected with them are brackets A² and A³. Rock shaft B is journalled in these 40 brackets and has fixed connection with trip member b near the center of the machine, said member b being preferably curved near its end for a purpose described below. Fixed to one end of said shaft is hook b' normally engaging beneath pin b² fixed to 45 arm D which is fixed to shaft D', the latter being journalled in said side bars. Fixed to shaft D' is arm D² carrying roller D³ and also arm D⁴ carrying roller D⁵. Spring 50 E may have one end suitably fixed to the frame of the machine and the other end is connected to arm D and tends normally to draw arm D downward and consequently raise rollers D³ and D⁵. Arm D has a projection carrying roller D⁶ which engages the

periphery of cam member F, the latter having fixed connection with shaft F' which is suitably mounted on the frame. Fixed also to said shaft is pinion F² driven by pinion F⁴ through chain F³, pinion F⁴ being driven in any suitable way, as by pinion F⁵. 60

The blanks, such as G and G', are fed by cooperating upper belt H and lower belt H' which may be actuated in any suitable 65 way. Upper presser rolls H² and lower presser rolls H³ may be used if desired.

Glue roll K is suitably mounted directly above roller D⁶ and has on its periphery glue which may be received from any suitable glue receptacle. Glue roll K' is suitably mounted directly above roller D⁶. 70

In operation envelope blank G is fed by the belts H and H' and its forward edge engages member b which is inclined forward and curved slightly upward so that it will never permanently block the feed of the blank. Blank G then pushes member b slightly upward and is fed beneath it, said upward movement swinging hook b' out of engagement with pin b² whereupon spring E acts to pull down arm D and consequently raises rolls D³ and D⁵ to press the flaps such as g and g' firmly against the rolls K and K' which thereupon deposit 80 glue on the top surfaces of said flaps. Arm D may be lowered because just after the hook b' releases the pin b² the roller D⁶ may move into the depressed portion f of the cam surface where it rides until the partially folded blank G has about reached the 85 position occupied by partially folded blank G' and then roller D⁶ rides up onto cam surface f' which brings pin b² up into normal position so that as blank G passes beyond member b the latter, under the influence of gravity, will drop down and swing hook b' under pin b², where the hook remains until the next blank moves member b. 90

It may be desired to vary the length of time during which the rolls D³ and D⁵ will be raised to accommodate, for example, blanks of different sizes and for this purpose I provide an adjustable cage L which is loosely mounted on the cam shaft, its outer edge being flush with the portion f' of the periphery of the cam. The cage may be swung to expose the desired amount of depressed portion f and I provide a set 95 100 105 110

of depressed portion f and I provide a set 110

of sockets f^2 in the cam, the desired two of which receive pins f^3 which engage the ends of slot L' to hold the cage in the desired position.

- 5 When the portion f' of cam F is in contact with the roll D^6 , the arm D is held in a position such that the pin b^2 is raised slightly from the hook b' to allow the strain of spring E to be removed from the hook b' .
10 This allows the hook b' to swing freely, as the friction between hook and pin b^2 is removed. Therefore, during the period of time in which the roll D^6 is in contact with portion f' , the finger b and hook b' are free
15 to be actuated by the passage of a blank. The passage of a blank raises the finger b sufficiently to disengage the hook b' from pin b^2 , thus allowing the roll D^6 to drop into the depression f on the cam after the
20 portion f' has passed by the roll due to rotation of the cam. During the entire contact of roll D^6 with portion f' , the pin b^2 is held just a little above normal and consequently the hook may swing under pin
25 b^2 without striking the latter.

What I claim is:

1. Mechanism of the character described comprising means to act upon a blank and other means to hold the first-mentioned
30 means against such action but actuated by the passage of a blank to release the first-mentioned means for such action; and mechanism to feed the blank past both of said means.
35 2. Mechanism of the character described comprising a member mounted to be swung

by a moving blank; a hook having fixed connection with said member; means to act upon said blank after the latter has swung said member and including a pin to interlock with said hook. 40

3. A machine for applying glue to blanks comprising a glue applying roll; a presser roll to cooperate with said glue roll; means to move said presser roll into such cooperative position; and means to hold the first-mentioned means against movement but actuated by a blank to release the first-mentioned means for movement. 45

4. Mechanism of the character described comprising a hook; a member mounted to be swung into position to act upon the blanks; an arm to swing the last-mentioned member, said arm having a pin to interlock with said hook and having a roller; a member having fixed connection with said hook and actuated by passing blanks to release said hook from said pin; a cam to cooperate with said roller; and a spring to move said arm and thereby swing the first-mentioned member into acting position when the hook and pin are unlocked. 50

5. Mechanism of the character described comprising a movable hook; a pin; a cam having a periphery operative to move said pin into position for engagement with said hook and having a portion projecting from said periphery operative to move said pin in a direction along the shank of said hook just prior to said engagement. 55 60 65

HAROLD J. GOSS.
